UNITED STATES PATENT OFFICE.

FRANK A. KUCERA AND CHARLES F. RUBEL, OF CHICAGO, ILLINOIS, ASSIGNEES TO UNION SPECIAL MACHINE COMPANY, OF CHICAGO, ILLINOIS, A CORPORATION OF ILLINOIS.

PROCESS OF CLOSING FILLED PAPER SACKS.

Application filed April 10, 1924. Serial No. 705,569.

To all whom it may concern:

Be it known that we, FRANK A. KUCERA and CHARLES F. RUBEL, citizens of the United States, residing, respectively, at Chicago, in the county of Cook, State of Illinois, have invented certain new and useful Improvements in Processes of Closing Filled Paper Sacks, of which the following is a description, reference being had to the accompanying drawing and to the figures of reference marked thereon:

The invention relates to new and useful improvements in the method of closing a filled sack, and more particularly a paper sack.

An object of the invention is to provide a method of stitching filled paper sacks, whereby the sacks may be closed one after another by stitches which are anchored in a fabric strip secured to the sack by the closing stitches and during the closing thereof.

A further object of the invention is to provide a method wherein the sack to be closed is trimmed to a predetermined height after being filled, and at the time of closing, and wherein the trimmed side edges of the bag or sack are enclosed in the folded strip secured to the bag by a line of stitching substantially parallel with the trimmed side edges.

In the drawings—

Figure 1 is a side view of a paper sack prior to the closing of the same;

Fig. 2 is an end view of the sack showing the side edges brought together for closing;

Fig. 3 is a side view of the closed sack;

Fig. 4 is an end view of the closed sack;

Fig. 5 is a view showing diagrammatically the steps whereby the sack is closed, said view showing the sack in side elevation, and

Fig. 6 is a view showing one form of means for carrying out the method, said view being taken at right angles to that of Fig. 5.

It has been a common practice prior to the present invention to close filled sacks by means of a line of stitching which passes through the side walls of the bag to be closed. Such a method of closing sacks, however, cannot be well used in connection with paper sacks, on account of the fact that the paper is very fragile and the

stitches will easily tear through the same. It has also been proposed to stitch a piece 55 of fabric to a paper sack before the sack is filled, and in such a position on the sack that the closing stitches can be passed through this strip. This is rather a slow process of closing and adds to the expense 60 of the sack.

The present method is directed to the closing of a paper sack of the ordinary construction without any fabric strip attached thereto during the making of the bag or 65 sack. The sack is filled, after which the side walls are brought together for closing. These side walls are trimmed a given distance above the support on which the bag rests so that the trimmed edges may be 70 passed into the strip guide which is capable of folding a strip of fabric about the trimmed side faces of the bag. The folded strip and the trimmed edges are then passed through a stitching mechanism whereby the 75 sides of the strip are stitched together and the stitches pass through the paper, thus holding the side walls of the bag in contact one with the other. The fabric strip becomes an anchorage for the stitches and 80 prevents said stitches from tearing through the paper.

If the content of the bag varies in quantity, the side walls of the bag will meet at different heights according to the amount 85 of content in the bag. The bag is, however, of sufficient height that it can be passed through a trimming mechanism and trimmed to a given height with the side edges even, regardless of the amount of content in the 90 bag. Then again, if the bag is not directly centered underneath the closing means, the edge of one side wall owing to the position of the content in the bag might be at a different level than the other. When, 95 however, the bag is filled and the side walls brought together over the top of the content of the bag and then said side walls trimmed, said walls will be even at a given distance above the support on which the bag rests so that they may be readily passed through the strip guide, and a strip folded over the same and the bag closed by the stitching mechanism operating at a given 100 height above the support.

In the drawings, the sack to be closed is

indicated at 1. Said sack is of the usual construction and the side faces 1^a and 1^b are brought together as shown in Fig. 2. The bag rests on the support 3 which may be 5 movable, if desired, or the stitching mechanism may be movable, or the bag may move on its support during the stitching thereof. The bag with the side walls brought together above the content therein 10 is first directed to a trimming mechanism which includes a reciprocating trimming blade 4. This trimming blade cooperates with a stationary blade on the support 5 and operates to cut the bag on the line x—x of 15 Figures 1 and 5. The cut off strip 6 is deflected away by means of a deflector 7. The two side walls are held together by means of a presser member 8 cooperating with the support 5. A fabric strip 9 is led through 20 a guide 10 of the English binder type. Said strip when it reaches the end of the guide is inverted and leads therefrom in a direction at right angles to the direction at which the strip enters the guide (see Fig. 25 5). The trimmed side walls of the paper sack pass through the end recess in the guide as clearly shown in Fig. 6, and thus pass in to the U-shaped folded portion of the fabric strip. The side walls of this 30 folded strip are indicated at 9^a and 9^b, and the U-shaped portion into which the side edges pass is indicated at 9^c. The stitches are formed by a needle 11 which reciprocates back and forth, penetrating the fabric 35 strip and the walls of the sack located between the side faces of the strip. Thus the needle forms a line of stitches 12 which are parallel with the cut edges of the paper sack and also parallel with the support on which 40 the sack rests.

It will be understood, of course, that the support and sewing head, one or the other may be adjusted for different size sacks, and after having been adjusted and properly fixed in adjusted position, the filled bag 45 is passed through first the trimming mechanism, then the strip guide mechanism, so that the side walls are trimmed, the strip folded about the side walls, and then to the 50 needle wherein the side faces of the strip are

stitched together, clamping the side walls of the bag therebetween.

By the improved method described above, the two side walls of the bag are always even when they reach the strip which enfolds the same and the stitching mechanism, regardless of the content of the bag, and whether or not the bag is centered beneath the stitching mechanism. The stitches are anchored in the fabric strip and thus the bag is held closed by the stitches. 55

Having thus described the invention, what we claim as new and desire to secure by Letters-Patent, is—

1. The method of closing filled paper sacks 65 including bringing the side walls of a sack together above the content in the sack, trimming said side walls on a line parallel to and at a given distance from the support on which the sack rests while being 70 closed, placing a fabric strip about the trimmed edge portions as said side walls are being trimmed, and simultaneously passing stitches through said fabric strip and the walls of the sack as the edges of the sack 75 are trimmed and embraced by the fabric strip so that the side walls of the paper sack are held clamped one against the other by a line of stitches anchored in the fabric strip and the sack closed thereby. 80

2. The method of closing filled paper sacks including bringing the side walls of the sack together above the content in the sack, trimming said side walls on a line parallel to and at a given distance from the support 85 on which the sack rests while being closed, directing the trimmed side walls of the sack through a strip guide whereby the fabric strip is folded and placed about the trimmed edge portions of the paper sack and simultaneously passing stitches through the fabric strip and the walls of the sack as said strip and sack leave the strip guide, so that the side walls of the paper sack are 90 clamped by the stitches which are anchored in the fabric strip.

In testimony whereof, we affix our signatures.

FRANK A. KUCERA.
CHARLES F. RUBEL.
